EDWARD R. KAST, OF BALTIMORE, MARYLAND, ASSIGNOR TO KAST INSETTING & GATHERING MACHINE COMPANY, OF NEW YORK, N. Y., A CORPORATION OF DELAWARE.

SIGNATURE-HANDLING MECHANISM.

1,180,725.

Specification of Letters Patent. Patented Apr. 25, 1916.

Application filed April 5, 1913. Serial No. 759,175.

To all whom it may concern:

Be it known that I, EDWARD R. KAST, of Baltimore, Maryland, have invented a new and useful Improvement in Signature-Handling Mechanism, which invention is fully set forth in the following specification.

The present invention relates to signature-handling mechanism, and one of the objects of the invention is to provide a simple, efficient and economical means for progressing signatures along the support on which they are mechanically or manually deposited. Heretofore it has been customary to progress groups of signatures along the saddle toward the stitching mechanism by means of a continuous conveyer, and to move said groups of signatures past said stitchers by means of reciprocating mechanism. I have experienced that when said continuous conveyers are employed and continuously driven, the signatures instead of being deposited on the support in front of the signature-engaging means or pins carried by said conveyer, are sometimes deposited on the points of said pins, and accordingly some of the signatures are knocked off of the support, and cause defective books. By my present invention, this disadvantage is obviated by the employment of a reciprocating carrier or conveyer provided with pivoted signature-engaging means that are elevated into and removed from the path of movement of the signatures along the support.

The invention will be better understood by reference to the accompanying drawings, illustrating one expression of the inventive idea, and wherein—

Figure 1 is an end view, partly in section, of a machine embodying my invention, with some of the parts removed for the sake of clearness; Fig. 2 is a perspective view, with parts broken away, illustrating the support on which the signatures are deposited, and the means for conveying the signatures along said support; Fig. 3 is a view of the reciprocating carrier on which the pivoted pins are mounted, and the support for said carrier, said parts being separated for the sake of clearness; and Fig. 4 is a detailed view of one of the pivoted pins that engage the groups of signatures.

Referring to the drawings, wherein like reference numerals indicate like parts, 10 is a support on which the signatures are deposited, here shown in the form of an in-

verted V-shaped saddle, said saddle being provided at its apex with a slot 11. Under said saddle there is mounted a suitable guide 12, which supports a carrier or conveyer 13, which is reciprocated in any suitable manner. A plurality of signature-engaging means is carried by said carrier 13, said means, as here shown, being in the form of pins 14 pivoted at 15 to said carrier, said pins passing through a slot 16. Any desired number of these signature-engaging means may be employed, and if the signatures are mechanically deposited on the support or saddle 10, one of said pins is preferably provided for each section of the machine which deposits the signatures. When the carrier 13 is moving in one direction, as here shown toward the left, the pins 14 are maintained in an upright position, as shown in Fig. 2, a spring member 17 carried by said carrier 13 and provided with a seat 18 engaging a depression 19 in said pin 14 for this purpose. When the carrier 13 is moving toward the right, the pins 14 are held in the depressed position shown in Fig. 3, by the engagement of a spring hook 20 mounted on said carrier 13, said hook engaging a perforation 21 in the lower end of each of said pivoted pins 14. Adjustably mounted on guides 12 is a plurality of stops 22, which project into the path of movement of said pivoted pins 14. As the carrier 13 moves toward the right (Fig. 2), each of said pins engages a corresponding stop 22, which results in each pin being forced into an upright position, where it is engaged by its corresponding spring member 17. While in this position, the upper ends of the pins 14 project through the slot 11 of the saddle, and said pins then engage the signatures which have been deposited on said saddle, and, upon the movement of the carrier 13 toward the left, progress the signatures along the saddle a distance corresponding to the width of one section of an insetting machine, if the signatures are mechanically deposited. As the carrier 13 reaches the end of its reciprocation toward the left, each pin 14 is engaged by the stop 22, which limits the extent of movement of said pin to the left, and this engagement disconnects each pin from its retaining member 17, and as the carrier 13 continues its further slight movement, the upper projecting portion of each pin 14 is forced down-

wardly, and the depression 21 in the lower end of each pin is engaged by one of the 5 spring hooks 20. When the spring hooks 20 are in engagement with the perforations 21, the upper end of each pin is below the path 10 of movement of the signatures, and the pins being held fixedly in this position, all danger 15 of them rising and contacting with the under face of the signatures supported on the saddle is obviated. It will thus be appreciated that each stop 22 acts to move its corresponding pin into the position shown in Fig. 2, upon the movement of the carrier 13 toward the right, except the extreme 20 left-hand stop, whereas each stop 22, with the exception of the first or extreme right-hand stop, acts on its corresponding pin to force the same into the position shown in Fig. 3, it being understood that the reciprocatory movement of any given pin is substantially limited by the distance between any two of the stops 22.

The carrier 13 is reciprocated in any suitable manner, but preferably the same is connected to, and in effect forms a continuation of, a carrier bar 13', which is reciprocated through suitable connections, as is fully described and illustrated in my application Serial No. 745,973, filed Feb. 3, 1913. Preferably, carrier 13 is secured to carrier 13' through connecting arms 26 and 27 (Fig. 2).

Carrier 13' is reciprocated along the support or saddle past any suitable stitching 35 mechanisms (not shown), and the groups of signatures which are fed past said stitching mechanisms are clamped against said carrier 13' by pivoted fingers or grippers 30. As here shown, said grippers or fingers are 40 mounted on a sleeve 31, which sleeve is reciprocated on a rod 32 having bearings at one end in a bracket 33. Reciprocatory movement is imparted to said sleeve 31 through an arm 35 (Fig. 1), one end of 45 which is secured to carrier 13' and the other end of which is forked and engages between two collars 36 keyed to sleeve 31. The pivoted fingers or grippers 30 are rocked toward and from the carrier 13', clamping 50 the groups of signatures against said carrier, and progressing them past the stitching mechanism, all as fully described in my application above referred to. It is sufficient to point out that the movement of said fingers or grippers 30 toward and away from 55 said carrier 13' is effected by means of a pin 37 secured to sleeve 31, which pin projects between two rods 38 and 39, carried by end pieces 40 (Fig. 1), said end pieces being 60 keyed to a rod 41, to which is connected a lever arm 42. The free end of said lever arm is connected to one end of a link 43, the other end of said link being connected to one arm 44 of a bell crank lever pivoted at 65 45, the other arm 46 of said lever being con-

nected to the upper end of a fork 47, provided with a roller 48 that engages a cam 49 keyed to shaft 25. When the roller 48 is in engagement with the unbroken surface of said cam, the fingers or grippers 30 are 70 clamping the groups of signatures against carrier 13', and when said roller 48 is in engagement with the cut-away portion of said cam 49, the fingers or grippers 30 are removed from the signatures, and are in 75 position for movement toward the right to engage the next group of signatures. After the groups of signatures have been stitched or stapled, they are preferably fed to any suitable delivery mechanism, by which they 80 are delivered from the machine.

As heretofore stated, the signatures may be manually deposited on the support or saddle 10, or any suitable means may be employed for depositing said signatures, such as those illustrated, described and claimed in my application Serial No. 508,160, filed July 17, 1909.

While, for the purpose of illustration, one embodiment of the inventive idea has been 90 herein described and illustrated in detail, it is apparent that the invention is not restricted to the particular structural embodiment illustrated and described, but that it is susceptible of embodiments conforming 95 to the definition of the invention given in the claims which follow.

What is claimed is:

1. In combination, a support for groups of signatures, a reciprocating carrier or conveyer movable longitudinally of said support, a plurality of signature-engaging means pivoted on said carrier or conveyer moving said signatures along said support, stationary means engaging said pivoted 105 means and projecting the same above said support and depressing the same beneath said support.

2. In combination, a support for groups of signatures, a reciprocating carrier or conveyer movable longitudinally of said support, a plurality of signature-engaging means pivoted on said carrier or conveyer moving said signatures along said support, means engaging said pivoted means and projecting the same above said support and depressing the same beneath said support, means holding said pivoted means in their projected position, and means holding said pivoted means in their depressed position. 110

3. In combination, a support for groups of signatures, a reciprocating carrier or conveyer movable longitudinally of said support, a plurality of signature-engaging means pivoted on said carrier or conveyer 115 moving said signatures along said support, stationary means engaging said pivoted means and projecting the same above said support and depressing the same beneath said support, means holding said pivoted means in their projected position, and means holding said pivoted means in their depressed position. 120

means in their projected position, and means holding said pivoted means in their depressed position.

4. In combination, a support for groups of signatures, a carrier or conveyer movable longitudinally of said support, a plurality of signature-engaging means pivoted on said carrier or conveyer moving said signatures along said support, means engaging said pivoted means projecting the same above said support and depressing the same beneath said support, resilient means holding said pivoted means in their projected position, and resilient means holding said pivoted means in their depressed position.

5. In combination, a support for groups of signatures, a reciprocating carrier or conveyer movable longitudinally of said support, a plurality of signature-engaging means pivoted on said carrier or conveyer moving said signatures along said support, and stationary means engaging said pivoted means projecting the same above said support and depressing the same beneath said support.

6. In combination, a support for groups of signatures, a reciprocating carrier or conveyer movable longitudinally of said support, a plurality of signature-engaging means pivoted on said carrier or conveyer moving said signatures along said support, means engaging said pivoted means and projecting the same above said support and depressing the same beneath said support, means holding said pivoted means in their projected position, and means holding said pivoted means in their depressed position.

7. In combination, a support for groups of signatures, a reciprocating carrier or conveyer movable longitudinally of said support, a plurality of signature-engaging means pivoted on said carrier or conveyer moving said signatures along said support,

stationary means engaging said pivoted means projecting the same above said support and depressing the same beneath said support, means holding said pivoted means in their projected position, and means holding said pivoted means in their depressed position.

8. In combination, a support for groups of signatures, a reciprocating carrier or conveyer movable longitudinally of said support, a plurality of signature-engaging means pivoted on said carrier or conveyer moving said signatures along said support, means engaging said pivoted means projecting the same above said support and depressing the same beneath said support, resilient means holding said pivoted means in their projected position, and resilient means holding said pivoted means in their depressed position.

9. In combination, a support for groups of signatures, a reciprocating carrier or conveyer movable longitudinally of said support, a plurality of signature-engaging means pivoted on said carrier or conveyer moving said signatures along said support, and stationary means arranged beneath said support engaging said signature-engaging means at the end of each reciprocatory movement of said carrier, elevating said pivoted signature-engaging means when said carrier moves in one direction and depressing said signature-engaging means when the carrier moves in the opposite direction.

In testimony whereof I have signed this specification in the presence of two subscribing witnesses.
